UNITED STATES PATENT OFFICE

105,204

DESIGN FOR AN ASH RECEIVER

Rudolph F. De Boer, Grand Rapids, Mich.

Application May 8, 1937, Serial No. 69,238

Term of patent 7 years

To all whom it may concern:

Be it known that I, Rudolph F. De Boer, a citizen of the United States, residing at the city of Grand Rapids, in the county of Kent and State of Michigan, have invented a new, original, and ornamental Design for an Ash Receiver, of which the following is a specification, reference being had to the accompanying drawing, forming a part thereof.

Fig. 1 is an angular top and front perspective

view of an ash receiver embodying the new design.

Fig. 2 is a front elevation of the same.

Fig. 3 is a top plan view of the same.

The back which is not shown is plain and unornamented.

I claim:

The ornamental design for an ash receiver as shown and described.

RUDOLPH F. DE BOER.
